Primary Examiner — Sanjeev Paul

(57) **CLAIM**

The ornamental design for a picnic blanket with leather carrier handle, as shown and described.

DESCRIPTION

FIG. 1 is a perspective view of a picnic blanket with leather carrier handle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof.

FIG. 8 is a front elevational view thereof, illustrated in an unfolded position; and,

FIG. 9 is a rear elevational view thereof, illustrated in an unfolded position.

The broken lines represent stitching that form a part of the claimed design.

1 Claim, 9 Drawing Sheets
